UNITED STATES PATENT OFFICE.

ROBERT R. SMITH, OF PHILADELPHIA, PENNSYLVANIA.

DOOR-CHECK.

SPECIFICATION forming part of Letters Patent No. 752,117, dated February 16, 1904.
Application filed October 29, 1903. Serial No. 179,051. (No model.)*To all whom it may concern:*

Be it known that I, ROBERT R. SMITH, a citizen of the United States, residing at Philadelphia, in the county of Philadelphia and State 5 of Pennsylvania, have invented a new and useful Door-Check, of which the following is a specification.

This invention relates to door-checks or devices for retaining doors when partly open in 10 any desired position, so as not to be blown shut by wind or closed by means of springs, with which they may be provided; and it has for its object to provide a device of this class which shall possess superior advantages in 15 point of simplicity, durability, and general efficiency.

With these and other ends in view my invention consists in the improved construction, arrangement, and combination of parts, which 20 will be hereinafter fully described, and particularly pointed out in the claims.

In the accompanying drawings, Figure 1 is a vertical sectional view showing a part of a door to which my invention has been applied, 25 the view including the operating mechanism and part of the connecting means of the device. Fig. 2 is a vertical sectional view on the line 2 2 in Fig. 1. Fig. 3 is a sectional view taken on the line 3 3 in Fig. 1. Fig. 4 is a sectional view taken through the lower 30 part of a door equipped with my improved check. Fig. 5 is a bottom view of the same. Fig. 6 is a detail view of the lower casing-cylinder. Fig. 7 is an edge view of a door to 35 which my invention has been applied. Fig. 8 is a perspective view of the two-part casing which forms the housing for the spring-actuated bolt of my improved door-check. Fig. 9 is a diagram showing the method of applying 40 my improved device to a door.

Corresponding parts in the several figures are indicated by similar numerals of reference.

1 designates a casing provided with an edge plate 2, which in practice is mortised into 45 the edge of the door, where it is secured by means of screws 3, as will be clearly seen in Fig. 1 of the drawings. The sides of this casing are connected by a pin 4, upon which is mounted a lever 5, the inner free end of which

is provided with a hook 6, having a rearwardly-extending lip 7. The sides of the casing 1 are also provided with openings 8. A shaft 10, preferably square in cross-section, extends transversely through the casing and through the openings 8 in the sides thereof. This shaft 55 carries a centrally-disposed cam 11, adapted to engage the lever 5. The cam 11 is provided with trunnions 12, journaled in the openings 8 of the casing, with a laterally-extending finger 14 and with a downwardly-extending hook 15, the latter engaging a transversely-disposed pin 16, the function of which is to form a stop for the cam when the device is in operative position. It will be obvious that by turning the cam in the direction indicated by 65 an arrow in Fig. 1 said cam will bear against the under side of the lever, raising the latter to the position indicated in dotted lines. A reverse movement will restore the cam and the lever to the position shown in full lines. 70

The casing containing the aforesaid elements is mortised into the door below the lock-casing, and the escutcheon 17 of the lock may be extended downwardly, or a separate escutcheon may be provided for the door-checking device. In either case the escutcheon is provided with an opening 8^a for the passage of the shaft 10, said opening being preferably surrounded by a flange forming a boss 18, which receives and guides the inner ends of 80 the handles 19, secured upon the ends of the shaft 10 by means of set-screws 20.

The under edge of the casing 1 is open for the passage of the links 21, the upper one of which is supported by the hook 6 of the lever 85 5, a vertical bore 22 extending through the door from the lower edge of the casing to the lower edge of said door, where it terminates in a socket or recess 23 of greater diameter than the bore. The socket or recess 23 is for 90 the reception of a cylindrical casing 24, which is made of separate parts or sections provided at their lower edges with flanges 25, perforated for the reception of screws 26, by means of which the two-part cylinder is secured in 95 the socket. The inner end of this socket has an opening 27 for the passage of a rod 28, the lower end of which terminates in a screw-

threaded point 29, at the upper end of which is formed an annular flange 30 of such a diameter as to move freely within the cylinder-casing. The latter also contains a helical spring 31, which is interposed between the flange 30 and the upper part of the casing and which exerts pressure in a downward direction against the flange.

The upper end of the rod 28 has a screw-threaded portion 32, which engages a correspondingly-threaded opening 33 in the lower end of a yoke 34, formed at the lower end of a rod 35, the upper one of which is hinged connected with the lowermost end of the links 21, the upper end of which is supported upon the lever, as already described. It will thus be observed that when the parts are properly connected together and adjusted the lever 5 supports the connecting device formed by the rods 28 and 35 and the links 21 and that a downward pressure is exerted upon the said connecting device by the spring 31.

36 designates a plug, which may be of wood or any other suitable material and which is capable of moving freely within the cylindrical casing 24, the upper end of said plug being connected with the rod 28 by the screw-threaded end 29 of said rod engaging the upper end of the plug which is secured in contact with the flange 30. The lower end of the plug 30 is annularly grooved, as at 37, and over it is fitted a cap 38, preferably made of rubber, which forms the contacting face of the door-check.

35 It will be seen from the foregoing description that when the handle 19 is turned to actuate the cam 11 in such a manner as to raise the lever 5 to the position shown in dotted lines in Fig. 1 the connecting devices composed by the links 21 and the rods 35 and 28 will be actuated against the tension of the spring 31, so as to elevate the plug 36, having the cap 38, into the cylindrical casing 24, where the parts will be supported by the hook 15 of the cam, which supports the lever 5 in the raised position indicated. When it shall be desired to retain the door in an open or partly-open position, a single turn in the opposite direction of the handle 19 will bring the hook 5 of the cam into engagement with the stub 16, which acts as a stop, while, the lever 5 being relieved from the support of the cam, the spring 31 will force the plug 36, having the cap 38, in a downward direction and 55 into engagement with the floor, thereby securely holding the door in the partly or entirely open position to which it may have been adjusted.

In order to connect my improved device operatively with the door, the latter is first prepared for its reception by forming a mortise at the proper place for the reception of the casing 1 and next forming the bore 22 from the lower edge of the door in an upward di-

rection until it registers with the casing at the 65 desired point. The lower end of the bore is also enlarged to form the socket 23, and proper recesses are formed for the reception of the edge plate 2 of the casing 1 and for the flange 25 of the two-part casing 24. A sufficient 70 number of links 21 are provided to make a connection of the desired length. It will be noticed that the uppermost link is somewhat longer than the remaining links. This is necessary only in order to provide for the proper 75 engagement of the uppermost link with the lever 5, as will be presently described. The rods 35 and 28 are connected by the screw-threaded connection afforded by the yoke 34, which is made of sufficient length to engage a 80 considerable length of the rod 28, which, however, is unscrewed as far as possible without disconnecting it from the yoke. The plug 36, which, with the cap 38, which is cemented or otherwise suitably secured thereto, constitutes 85 the bolt, is connected with the lower end of the rod 28, and these parts, together with the spring 31, may now easily be assembled in the two-part cylinder, which latter is properly secured in the recess 23, provided for its reception. The rods and links are pushed upwardly 90 through the bore 22 until the uppermost link may be caught at the inner end of the mortise provided for the reception of the casing 1. The links 22 will enable the uppermost link to 95 be brought out through the mortise, as shown in Fig. 9 of the drawings, when it may be readily connected with the hook 6 of the lever 5, the casing 1 being held in close proximity to the edge of the door in the meanwhile. The said 100 casing is then inserted into the socket, thus causing the bolt to be pressed outwardly from the casing by the spring 31. The said bolt is now by the use of the fingers or by some suitable tool turned from left to right, thus causing 105 the screw-threaded portion 32 of the rod 28 to pass into the yoke 34 at the lower end of the rod 35 and enabling the desired adjustment to be made—that is, permitting the necessary portion of the bolt to protrude below the lower 110 edge of the door. This adjustment, of course, may be readily ascertained, and it may be made more or less effective, according to the size and weight of the door to which the device is applied. The shaft 10 of the handles 115 is now adjusted in position, as well as the edge plate of the casing 1, and the device is then 120 in condition for operation.

From the foregoing description, taken in connection with the drawings hereto annexed, the operation and advantages of my invention will be readily understood. The device is simple and effective in use, and, as will be seen, provision has been made for its application to doors of various dimensions in such a 125 manner that an effective adjustment may always be had.

I have in the foregoing described a simple

and preferred construction of my invention; but I desire it to be understood that I do not necessarily limit myself to the precise structural details herein set forth, but reserve the right to any changes, alterations, and modifications which may be resorted to within the scope of my invention and without departing from the spirit or sacrificing the utility of the same.

10 Having thus described my invention, I claim—

1. In a device of the class described, a door having a vertical bore enlarged at its lower end and terminating in a mortise at its upper end, a casing in said mortise, a lever in said casing having a hooked end extending over the bore, means for manipulating said lever to raise and support the inner end thereof, a downwardly-spring-actuated bolt in the enlarged lower end of the bore, and connecting means between said bolt and the hooked end of the lever, said connecting means including two adjustably-connected rods and a chain connecting the upper rod with the hooked end of the lever.

2. In a device of the class described, a door having a vertical bore enlarged at its lower end and terminating in a mortise at its upper end, a casing in said mortise, a lever in said casing having a hooked inner end extending over the bore, a two-part casing in the enlarged lower end of said bore, a downwardly-spring-actuated bolt seated in said casing, a rod having screw-threaded connection with the upper end of the bolt provided with a flange abutting upon the upper end of said bolt, said rod extending upwardly into the bore, a second rod having screw-threaded connection with the first or lower rod, and a chain connecting the upper rod with the inner hooked end of the operating-lever.

3. In a device of the class described, a door having a vertical bore enlarged at its lower end and terminating in a mortise at its upper end, a two-part vertically-divided casing seated in the enlarged lower end of the bore, a downwardly-spring-actuated bolt movable in said casing and having an elastic cushion of a diameter not exceeding that of the bolt, and means for withdrawing said bolt and cushion.

into the casing against the tension of the spring and for retaining the same in such withdrawn position.

4. In a device of the class described, a bolt consisting of a wooden cylinder having an annular groove, and a cap engaging said groove and thereby connected with the cylinder, said elastic cap being of an extreme diameter not exceeding the diameter of the bolt.

5. In a device of the class described, the combination with a downwardly-spring-actuated bolt, of operating means comprising a hooked lever and a cam adapted to raise said lever and to sustain it in a raised position, and connecting means including a rod connected with the bolt and having a screw-threaded upper end, a rod provided with a yoke having screw-threaded connection with the upper end of the lower rod, and a chain comprising a plurality of links, the lower one of which is connected with the upper connecting-rod and the upper one of which is connected with the hooked end of the lever.

6. In a device of the class described, the combination with a connecting-rod having a pointed screw-threaded lower end and an annular flange, a bolt comprising a wooden plug having screw-threaded connection with said rod below the flange and provided with an annular flange, and an elastic cap engaging said flange and of an extreme diameter not exceeding that of the wooden plug constituting the bolt.

7. In a door-checking device, a lever mounted in a suitable casing and having a hooked inner end and a bolt adapted to be operated by said lever, in combination with connecting means including links adapted to be inserted into the mortise provided for the reception of the lever-carrying casing and to be drawn forwardly through said mortise for engagement with the hooked end of the lever.

In testimony that I claim the foregoing as my own I have hereto affixed my signature in the presence of two witnesses.

ROBT. R. SMITH.
